UNITED STATES PATENT OFFICE.

SISSAK K. OUZOUN-BOGHOSIAN, OF NEW YORK, N. Y.

WATER-MIXER.

1,316,637.

Specification of Letters Patent. Patented Sept. 23, 1919.

Application filed January 11, 1918. Serial No. 211,395.

To all whom it may concern:

Be it known that I, SISSAK K. OUZOUN-BOGHOSIAN, a subject of the Sultan of Turkey, residing at New York, in the county of New York and State of New York, have invented certain new and useful Improvements in Water-Mixers, of which the following is a specification.

This invention relates to improvements in water-mixers which are adapted to be attached to the discharge spouts of two hot and cold water faucets.

This invention is a detachable and adjustable telescoping metallic tubular device, intended to be attached between and on two faucets of any hot and cold water supply system, and by means of the single discharge spout of this device to supply hot and cold water mixed at any temperature desired, as well as hot water alone or cold water alone to be supplied from the same discharge spout of the mixer.

This invention being an adjustable attachment, complete in itself, can be easily attached between and on the discharge spouts of two faucets of a wash-basin, sink or the like, and as easily removed when the use of it is not desired, and being of a simple construction it is inexpensive.

The object of my invention is to provide a cheap and practical yet simple and attractive water-mixer adapted to be readily attached between and on and removed from two hot and cold water faucets, and therefore to discharge either hot or cold water or mixed as may be desired.

Another object of my invention is to provide an adjustable water-mixer with telescoping tubular adjustments, thus eliminating the exposure of more parts for the adjustments, and to enable the use of shortest ways, straight tubes, the mixer being adjustable as to the directions of the telescoped parts.

Another object of my invention is to provide a water-mixer which is a combination of several separate metallic tubular parts detachably connected together, which can be readily taken all apart and put together, and different combinations can be made from the same parts.

Another object of my invention is to provide a water-mixer with two styles of mouthpiece parts, one with an inlaid thick rubber ring and the other with an outer rubber tube, which are to be attached to the discharge spouts of any two faucets, so that, a pair of either style or in combination can be used as the circumstances may require.

The nature, characteristic features and scope of the invention will be more fully understood from the following description taken in connection with the accompanying drawings forming part hereof and in which:

The eight different forms of the mixer of the invention are adjusted to the flat especially for these drawings

Figure 1 is a view in partly sectional front elevation of the mixer of the invention. Fig. 2 is a view in partly sectional back elevation of a modification of the mixer of the invention. Figs. 3, 4, 5, 6, 7 and 8 are views in partly sectional front elevations of the modifications of the mixer of the invention.

Similar reference letters refer to similar parts throughout the drawings.

Referring to the drawings, Figs. 1 to 8 inclusive are all combinations of separate metallic tubular parts, said parts being telescopically and detachably connected together, but small rubber members are used for connecting and water-tightening purposes. The telescopically connected parts have telescopic joints and are capable of lengthwise adjustments, and all these parts are capable of being readily taken apart and put together. These mixers are made of thin sheet-metal and preferably finished nickel-plated.

In Fig. 1, E A B C and F D C are two styles of mouthpiece parts. E and F are rubber tubular members fitted to the parts A and D respectively, by which the mixer is attached to the faucets. M N, M N are two L-shape tubes. J K L, J K L are two two-way communicating T-shape tubes, the third way closed by R, R washers. G H I is a T-shape tube, the stem tube G of which serving as a discharge-spout to the mixer. Rubber rings X are fitted at all telescopic joints. Said three T-shape tubes, two L-

shape tubes and two mouthpiece parts are telescopically and detachably connected together. Also a pair of either E A B C or F D C mouthpiece parts, as in Figs. 7 and 5 8, can be used in combination.

In Fig. 2, the three T-shape tubes K J L, H G I, K J L are integrally connected instead of being telescopically connected, also the L-shape tubes M N, M N are integrally 10 connected to mouthpiece parts E A B C, F D C, thus forming E A B C M N, F D C M N mouthpiece parts, otherwise being the same as in Fig. 1.

In Fig. 3, three T-shape tubes K J L, H G 15 I, K J L and two mouthpiece parts E A B C M N, F D C M N are telescopically connected together. Also a pair of either E A B C M N or F D C M N mouthpiece parts can be used in combination.

20 In Fig. 4, three T-shape tubes K J L, H G I, K J L and mouthpiece parts E A B C, F D C are telescopically connected together, and the connecting tubes C, C of the mouthpiece parts A B C, D C are disposed at acute 25 angles to the parts A B and D respectively instead of at right angles as in Fig. 1.

In Fig. 5, the T-shape tube H G I and mouthpiece parts E A B C, F D C are telescopically connected together. Also a 30 pair of either E A B C or F D C mouthpiece parts can be used in combination.

In Fig. 6, the T-shape tube H G I and mouthpiece parts E A B C, F D C are telescopically connected together, and E A C 35 mouthpiece part is fitted to rubber tubular member F. This combination is adapted for two faucets disposed at different heights.

By the arrangements and construction of parts described above and shown in the 40 drawings it will be evident that the hot and cold water is mixed in passing through the discharge spout of the mixer.

However, I do not limit myself to the forms described herein and shown in the 45 drawings, as it can be readily seen that, the mixer can be constructed in many different forms without departing from the principles of this invention.

Having described my invention what I 50 desire to secure by Letters Patent of the United States and claim is:

1. An adjustable telescoping metallic tubular water-mixer adapted to be removably attached between and on the discharge spouts 55 of any two hot and cold water faucets, said mixer being a combination of seven separate metal parts and a set of rubber members, said seven metal parts consisting of three T-shape tubes, two L-shape tubes and two 60 mouthpiece parts, said set of rubber members consisting of a set of thin rubber rings and two rubber tubular members, said seven metal parts being telescopically and detachably connected together, the stem tube of one

of said T-shape tubes serving as a discharge 55 spout to said mixer, said two mouth-piece parts having fitted thereto said tubular rubber members, said mixer adapted to be attached to the discharge spouts of said hot and cold water faucets by said rubber tubular members, said telescopic joints being covered with said thin rubber rings, all substantially as set forth.

2. An adjustable telescoping metallic tubular water-mixer adapted to be removably 70 attached between and on the discharge spouts of any two hot and cold water faucets, said mixer being a combination of five separate metal parts and a set of rubber members, said five metal parts consisting of three 75 T-shape tubes, and two mouthpiece parts, said set of rubber members consisting of a set of thin rubber rings and two rubber tubular members, said five metal parts being 80 telescopically and detachably connected together, the stem tube of one of said T-shape tubes serving as a discharge spout to said mixer, said two mouthpiece parts having fitted thereto said rubber tubular members, said mixer adapted to be attached to the discharge 85 spouts of said hot and cold water faucets by said rubber tubular members, said telescopic joints being covered with said thin rubber rings, all substantially as set forth.

3. An adjustable telescoping metallic tubular water-mixer adapted to be removably 90 attached between and on the discharge spouts of any two hot and cold water faucets, said mixer being a combination of three separate metal parts and a set of rubber members, 95 said three metal parts consisting of one T-shape tube and two mouthpiece parts, said set of rubber members consisting of a set of thin rubber rings and two rubber tubular members, said three metal parts being 100 telescopically and detachably connected together, the stem tube of said T-shape tube serving as a discharge spout to said mixer, said two mouthpiece parts having fitted thereto said rubber tubular members, said 105 mixer adapted to be attached to the discharge spouts of said two hot and cold water faucets by said rubber tubular members, said telescopic joints being covered with said thin rubber rings, all substantially as set forth.

4. An adjustable telescoping metallic tubular water-mixer adapted to be removably 110 attached between and on the discharge spouts of any two hot and cold water faucets, said mixer being a combination of five separate 115 metal parts and a set of rubber members, said five metal parts consisting of three T-shape tubes and two mouthpiece parts, said set of rubber members consisting of a set of thin rubber rings and two rubber tubular members, said three T-shape tubes being 120 affixed together, said five metal parts being telescopically and detachably connected to-

gether, the stem tube of one of said T-shape tubes serving as a discharge spout to said mixer, said two mouthpiece parts having fitted thereto said rubber tubular members, 5 said mixer adapted to be attached to the discharge spouts of said faucets by said rubber tubular members, said telescopic joints being

covered with said thin rubber rings, all substantially as set forth.

In testimony whereof I affix my signature. 10
SISSAK K. OUZOUN-BOGHOSIAN.
